and scaling can still result in sparse and ill-conditioned matrices. The *gibson* and *carpet* benchmarks are not sparse enough to benefit from this approach, but the *airplane* and *cameraman* benchmarks are sparse enough to benefit from this approach. The *cameraman* benchmark is a 512x512 grayscale image of a man's face. The *airplane* benchmark is a 256x256 grayscale image of a Boeing 747 airplane. The *cameraman* and *airplane* benchmarks are both sparse enough to benefit from this approach.

UNITED STATES PATENT OFFICE

HAIR PIECE, TOUPEE, OR WIG

Victor Jack Gordon, London, England

Application December 15, 1944, Serial No. 568,285
In Great Britain October 21, 1944

1 Claim (Cl. 132—53)

This invention relates to hair pieces, toupees or wigs and more particularly to what may be termed edge forming elements for use therewith.

As is known, one of the difficulties involved in connection with the production of hair pieces, toupees or wigs is that of forming the front, side or other marginal edges of the same in such manner that the edges will lie close to the skin and give the desired finish and realistic effect or make it difficult to detect that the hair is not genuine and attached by roots to the wearer's head in nature's own way. 5 10

In accordance with the present invention, these and other attendant difficulties are overcome by the use of a separate edge forming element which comprises a metallic or other strip having a series of fine wires or threads projecting laterally therefrom and which is incorporated in or applied to the edge of the hair piece, toupee or wig so as to produce the desired realistic or blending effect or finish.

In some forms of the invention particularly for use on a wig and at the back thereof, the aforesaid edge forming element may be composed of a single strip of metal, metal foil or the like having projecting laterally therefrom at one side thereof a series of separate fine wire threads.

In other forms of the invention, particularly for use at the side or front portion of a toupee, the aforesaid edge forming element may be composed of two superposed strips of metal, metal foil or the like which are interconnected with each other as, for example, by soldering and each of which has a series of fine wires projecting laterally therefrom at one side thereof. Thus, for example, in carrying the invention into effect according to one convenient mode, the lower part of such a composite hair line may consist of a thin flat strip of metal or metal foil having a series of extremely fine wires or threads secured thereto or soldered thereon and projecting laterally from one side of the same whilst the upper part of the edge forming element may consist of a similar strip which is also provided with a series of extremely fine wires projecting laterally from one side thereof.

According to another form of the invention, the edge forming element is composed of two superposed strips of metal, metal foil or the like each having a series of fine wires or threads projecting laterally from one side thereof, and netting, cotton gauze, hair lace or a fine wire gauze interposed therebetween for the attachment or looping there-to of hair strands.

In practice, the aforesaid fine wires or threads

are selected to suit the texture and colouring of the hair and, as will be appreciated, the metallic strip may be bent to conform with the shape of the head or the article to which the edge forming element is being applied.

In order that the said invention may be clearly understood and readily carried into effect, the same will now be more fully described with reference to the accompanying drawing, in which:

Fig. 1 shows one form of edge forming element produced in accordance with the invention;

Fig. 2 shows another form of edge forming element made up of two units of the form shown in Fig. 1; and

Fig. 1, and Fig. 3 shows another form of edge forming element produced according to the invention and made up of two units of the form shown in Fig. 1 and an interposed strip of netting or the like, said edge forming element being ready to receive the hair strands or loops preparatory to being applied to or incorporated in an edge portion of a hair piece, toupee, wig or the like.

In the form of the invention shown in Fig. 1 of the accompanying drawing, the edge forming element consists of a single flat strip A of pliable metal or metal foil which is about one-eighth of an inch wide and is provided with a series of fine wire threads B which are secured thereto as, for example, by being soldered in position thereon at their ends so that they project laterally therefrom at one side thereof and are disposed in the same plane or substantially the same plane as the strip. The wire threads B may be constituted by lengths of fine wire, e. g. silver wire, copper wire or steel wire, having a gauge of the order of 39 to 42 arranged side by side with their anchored or soldered ends disposed parallel with one another and spaced from each other by spacings of the order of one thirty-second to one-fiftieth of an inch. The wires or threads may be of the same length but, in many instances, it is preferable to use different lengths, so that an irregular or undulating edge is formed by the free ends of the assembled elements. Although the wires or threads have been shown as extending outwardly at right angles or substantially at right angles to the length of the strip A, it will be appreciated that they may be disposed at any angle thereto, the angularity being dependent upon the position in which the edge forming element is required.

The unit thus produced and shown in Fig. 1 of the accompanying drawing is particularly suitable for application to or incorporation in the back of a wig for a neck line and, if desired, the edge portion of the foundation of the wig may be

formed with a groove to receive the same or the part thereof constituted by the strip A. It will be appreciated that the latter may readily be bent to conform with the shape of the head of the wearer.

In the form of the invention shown in Fig. 2 of the accompanying drawing, the edge forming element is a composite one built up of two superposed elements or strips of metal or metal foil each having a series of extremely fine wires or wire threads secured thereto, this form of the invention being particularly suitable for use at or in the side portions of a wig or toupee. The two elements (each of which is of the form shown in Fig. 1) are suitably secured together as, for example, by solder and, preferably the wire threads of the upper element are slightly longer than the wire threads of the lower element and the two elements are secured to one another in such manner that one set of wire threads is staggered with respect to the other such set of threads or, alternatively, the wires of each set are differently spaced.

The edge forming element shown in Fig. 3 of the accompanying drawing is made up of two units of the form shown in Fig. 1 and a strip of C interposed netting, cotton gauze, hair lace or fine wire gauze, the arrangement being such that the fine wires or threads extend outwardly be-

yond the netting or the like. The two units are suitably secured together as, for example, by solder and the netting or the like serves for the attachment or looping thereto of hair strands.

5 The netting or the like is preferably coloured a light cream colour to enable the wig maker the more readily to see the same when looping or knotting the hair strands thereon and the composite edge forming element thus obtained may, after the hair strands have been applied thereto or looped in position thereon, be readily bent to conform with the shape of the head of the wearer. Such edge forming element is particularly suitable for use at the front portion of a toupee and, if desired, the foundation of the toupee may be formed or grooved so that it is adapted to accommodate the edge forming element.

I claim:

20 For application to the edge of a hair-piece, toupee, wig or the like, a separate edge forming element composed of two superposed flexible strips each having a series of fine wires projecting laterally from one side thereof, the wires of the respective strips being of different lengths and 25 staggered with respect to each other so that an irregular edge is formed by their free ends, and a fine netting secured to said superposed strips for the attachment thereto of hair strands.

VICTOR JACK GORDON.
